her attorney

UNITED STATES PATENT OFFICE.

MABEL M. STURGIS, OF BURLEY, IDAHO.

UNDERWAIST.

1,415,616.

Specification of Letters Patent. Patented May 9, 1922.

Application filed August 25, 1920. Serial No. 405,895.

To all whom it may concern:

Be it known that I, MABEL M. STURGIS, citizen of the United States, residing at Burley, in the county of Cassia and State of Idaho, have invented certain new and useful Improvements in Underwaists, of which the following is a specification.

My present invention relates to underwaists, and particularly to a garment of this character intended and adapted for use in place of a corset.

An object is to provide a garment which gives an adjustable lapping front portion over the abdomen to provide support therefor, while leaving the bust and upper portions of the body entirely free and unrestricted.

A further object resides in so constructing the garment that the skirt and waist of the wearer may be pinned to the same, as may also the hose supporters, and that the weight of these portions of the apparel secured to the underwaist will be carried from the shoulders of the wearer.

A still further object is to provide an underwaist which can be easily made of heavy drill, or of lighter material as desired, thus being readily laundered, and which makes it possible for the wearer to discard corsets and yet to obtain support for the clothing and a natural support for the abdominal portions of the body.

With these and other objects in view, which will be apparent from the drawings, specification and claims, this invention includes certain novel features of construction and combinations of parts which will now be set forth.

In the drawings:

Figure 1 is a view in front perspective showing my improved underwaist in use.

Fig. 2 is a similar view in back perspective.

Fig. 3 is a perspective view in rear elevation showing the underwaist opened out to better illustrate the construction of the same.

The body portion of the garment is made up of heavy drill or of lighter material, to suit the requirements and demands of the wearer, and is cut and fitted so that the back thereof will conform to the contour of the body. At the sides of this back portion 1 the tapering front portions 2 and 3 are secured, and shoulder straps 4 and 5 made integral with the back portion are brought

over and secured at their ends by being stitched to the front portions 2 and 3.

To give a finish and additional strength, and to prevent stretching, it is preferable that all seams be taped as shown at 6, and that a binding tape 7 be secured on the edges of the material.

On the forward loops of the shoulder straps 4 and 5 straps 8 and 9 are secured, portions of a hooked, snapped, or other fastening being provided at 10 and 11.

A reinforcing strip 12 is sewed on the back portion 1 at the waist line, and reinforcing patches 13 and 14 are sewed at the corners of the front portions 2 and 3 and along the lower edge of the garment substantially at those points where the front portions join the back. It is preferable that the edge binding 7 be secured over these reinforcing patches, and extended around straps 8 and 9 to thus give a finish to all portions of the garment, however under some conditions it may be found desirable to employ elastic or webbing strips for the straps 8 and 9 under which circumstances binding will not be necessary.

In the use of my improved underwaist the arms are slipped through the loops of the shoulder straps 4 and 5, and the tapering front portions 2 and 3 are drawn forward and are overlapped as shown in Fig. 1. These ends are secured by pins passed through the reinforcing patches 13 and through the material of the front portions 90 or, as shown in Fig. 1, the fastenings of hose supporters 15 are used to secure these ends. Other hose supporters are secured through reinforcing patches 14 to depend from the waist. In this way the reinforced back is presented for securement of the skirt and waist, the hose supporters are carried at the lower edge of the underwaist, and the weight carried by these parts hangs from the shoulders. The overlapping front portions are adjusted upon each occasion and make a smooth fitting support for the abdomen, while the bust of the wearer is entirely unrestricted.

While, in the foregoing, I have described specific embodiments, and have mentioned only certain possible modifications, it will be appreciated that in practice I do not limit myself to such specific details as herein set forth, but may resort to any practical modifications falling within the scope of the invention as defined in the appended claim.

I claim:

An underwaist including with a shaped back portion, substantially triangular front portions secured at the sides of the back portion to have their tapered ends overlapped over the abdomen of the wearer and secured, shoulder straps extending from the top edge of the back portion looped over and con-

nected at their free ends on the tapered edges of the front portions to present arm loops, and straps connected with the forward loops of the shoulder straps to be fastened across the chest of the wearer to hold the shoulder straps in place.

In testimony whereof I affix my signature.

MABEL M. STURGIS.
